STAPLING MACHINE

Herbert W. Marano, Brooklyn, N. Y., assignor to
 Wilson-Jones Company, Chicago, Ill., a corpora-
 tion of Massachusetts

Application January 8, 1953, Serial No. 330,337

6 Claims. (Cl. 1—3)

1

The present invention relates to staple drivers, and in particular to staple drivers comprising a base, an upper cover member including a driving ram and an interpositioned lower member constituting a staple magazine. The present invention is a continuation-in-part of the invention disclosed and claimed in my copending application Serial No. 158,462, filed April 27, 1950, now Patent No. 2,624,878, issued January 13, 1952, and relates specifically to the means for releasably securing the magazine to the cover and driving ram assembly. The particular details of the staple driving operation are not important to an understanding of the present invention, and these will be detailed in the copending case.

In previous devices of this general construction, in order to provide a reasonably good engagement between the magazine and cover, it was necessary to manufacture and assemble the parts to close tolerances. This, of course, made assembly a relatively slow process and greatly increased the cost of manufacture of the device. The main object of the present invention, therefore, is the provision of an interengagement between the magazine and cover which may be achieved easily and simply, using parts with relatively wide tolerances, thereby to increase assembly and reduce the over-all cost of the device, while retaining all the necessary operational functions, as ready relative displacement of the cover and magazine.

The present invention is characterized by the use of reversely bent spring legs depending from the underside of the cover interengaging the forwardly bent edges of the front wall of the magazine. The depending spring fingers are very easily displaceable to permit same to ride over the front wall of the magazine during engagement and disengagement of the cover and magazine.

In the drawings annexed hereto, and forming a part hereof,

Figure 1 is a side elevational view of one form of staple driving device embodying the improvement of the present invention, with a portion thereof broken away and sectioned;

Figure 2 is an enlarged front elevational view of the magazine and cover assembly, with the cover sectioned to reveal structural details;

Figure 3 is an enlarged side elevational view of the front of the cover and magazine assembly with the cover sectioned to reveal structural details; and

Figure 4 is a section on the line 4—4 of Figure 3.

The normally horizontally extended base 10, a channel-shape staple magazine assembly 12 open at the top thereof, and a cover 14 of inverted

2

channel-shape are all pivotally pinned together at the rear thereof, as indicated by reference numeral 16. A pair of spaced apart standards are mounted atop base 10 between which the staple magazine 12, the lower member, and cover 14, the upper member, are pivotally disposed. Cover 14 is provided with a depending skirt 18 along the sides and front. On the underside of the cover, there is secured as by rivets 20, 20 a driving member 22 of flat spring steel, having an integral downwardly projecting staple driving component 24 at the forward end thereof. A cover guide 26 is provided comprising an inverted channel shaped stamping pivoted with cover 14 at 16 and having a forwardly extended T-tongue 28 projecting through a rectangular opening 30 in driving blade 24. Spring means (not shown) are provided within cover 14 normally to urge guide 26 downwardly from cover 14 into the relation shown in Figures 2 and 3.

Between drive member 22 and the underside of cover 14, there is disposed a flat member of spring metal 32 having a bifurcated, downwardly angled component 34 at the front thereof, defining spring legs 36, 36 between ram blade 24 and the front skirt 18. The terminals of legs 36, 36 are reversely and rearwardly bent, as at 38.

Magazine 12 is generally U-shaped, open at the top, and is provided with a front wall 40 extended above the level of the side walls 42 thereof, said front wall being provided at its upper end with a pair of forwardly curved lips 44, 44 spaced apart the same distance as legs 36, 36 and bends 38, 38.

As will be readily understood, magazine 12 comprises the usual staple receptacle and means therein to urge the staples toward the front thereof, at which point the staples are driven downwardly against base 10 when cover 14 is depressed and blade 24 driven downwardly against the rear face of magazine front wall 40. Normally, it is desirable that magazine 12 and cover 14 swing as a unit about pivot 16. However, it becomes necessary to obtain access to the interior of magazine 12 to load staples thereinto, and the cover and magazine must be separated.

The cover and magazine are shown in Figures 2, 3 and 4 engaged for movement simultaneously with respect to base 10. Forwardly bent lips 44, 44 extend over the ends of reverse bends 38, 38. During operation of the device, when cover 14 is manually depressed against base 10 bearing magazine 12 along with it, cover 14 moves downwardly with respect to said magazine and legs 36, 36 ride downwardly along the outer face of magazine wall 40 until driver blade 24 ejects the staple in line

with it. As pressure is released on the cover, it will first rise with respect to magazine 12 until bends 38, 38 bear against and engage lips 44, 44 whereupon the magazine will then be borne along with the cover.

When it is desired to separate the cover from the magazine to expose the interior of the latter, the sides of the magazine near the front thereof are held in one hand, while the cover is grasped in the other hand and simply pulled apart, with the bends 38, 38 riding over and free of lips 44, 44. Due to the springiness of bends 38, 38 and their associated legs, it is obvious that no great tolerances are required, and that even a "slop" fit will nevertheless be effective for all practical purposes.

The parts of my device need not be machined, but may be stamped easily and quickly, and relatively inexpensively. With suitably spaced guide apertures for the riveting 20, the cover, driver, guide and spring may be assembled very easily and even by relatively unskilled labor. The features of the present invention are the forwardly arched lips 44 at the top of the front wall of the magazine and the cooperating spring legs 36 which are rearwardly biased (seen Figures 1 and 3) in combination with the reverse bends 38, 38 at the ends thereof.

Having now described my invention, what I claim and desire to secure by Letters Patent are:

1. In a stapling machine comprising a base, an upper cover member of inverted channel shape and a staple driver blade projecting downwardly therefrom at the front end thereof and spaced from said front end, with the rear end of the upper member being pivotally supported on the rear of the base, a lower member of channel shape open at the top and forming a magazine for staples, the rear end of the lower member being pivotally supported at the rear end of the upper member, a driver guide between the upper and lower members interengaged with the upper member to pivot therewith, the cover and the guide being manually separable from the lower member substantially simultaneously to expose the interior of said lower member, and releasable spring means depending from the underside of the upper member between the front thereof and the driver blade yieldably to engage and retain therewith the lower member.

2. In a stapling machine comprising a base, an upper cover member of inverted channel shape and a staple driver blade projecting downwardly therefrom at the front end thereof and spaced from said front end, with the rear end of the upper member being pivotally supported on the rear of the base, a lower member of channel shape and having an upstanding front wall, said lower member being open at the top and forming a magazine for staples, the rear end of the lower member being pivotally supported at the rear end of the upper member, a driver guide between the upper and lower members interengaged with the upper member to pivot therewith, the cover and the guide being manually separable from the lower member substantially simultaneously to expose the interior of said lower member and releasable spring means depending from the under-

side of the upper member between the front thereof and the driver blade, said spring means terminating in a reverse bend yieldably to engage the front wall of the lower member and retain therewith the said lower member.

5. In a stapling machine comprising a base, an upper cover member of inverted channel shape and a staple driver blade projecting downwardly therefrom at the front end thereof and spaced from said front end, with the rear end of the upper member being pivotally supported on the rear of the base, a lower member of channel shape having an upstanding front wall terminating in forwardly curved portions, said lower member being open at the top and forming a magazine for staples, the rear end of the lower member being pivotally supported at the rear end of the upper member, a driver guide between the upper and lower members interengaged with the upper member to pivot therewith, the cover and the guide being manually separable from the lower member substantially simultaneously to expose the interior of said lower member and releasable spring means depending downwardly and rearwardly from the underside of the upper member between the front thereof and the driver blade, said spring being bifurcated at its lower end, the bifurcations terminating in reverse bends yieldably to engage the portions of the front wall of the lower member and retain therewith the said lower member.

20. In a stapling machine comprising a base, an upper cover member, a driver guide between the upper and lower members interengaged with the upper member to pivot therewith, the cover and the guide being manually separable from the lower member substantially simultaneously to expose the interior of said lower member, and releasable spring means depending from the underside of the upper member between the front thereof and the driver blade yieldably to engage and retain therewith the lower member.

25. In a stapling machine comprising a base, an upper cover member, and an intermediately disposed lower member, a staple driving blade projecting downwardly from the upper cover member at the front end thereof and spaced rearwardly of said front end, the rear end of said upper member being pivotally supported on the rear of the base, the lower member forming a magazine for staples, the rear end of said lower member being pivotally supported at the rear end of the base on a common pivot with the upper member, the lower member having a front wall the top of which extends forwardly of the lower member, the front end of the cover being manually separable from the front end of the lower member to expose the magazine, and releasable spring means depending from the underside of the upper member yieldably to engage the front wall extension of the lower member.

30. In a stapling machine as in claim 4, wherein the releasable spring means depend from the upper member between the driver blade and the front end of said cover member.

35. In a stapling machine as in claim 5, wherein the end of the releasable spring means is rearwardly extended.
